(57) **CLAIM**

The ornamental design for a portable front projection screen, as shown and described.

DESCRIPTION

FIG. 1 is a front and top perspective view of the portable front projection screen shown in a closed configuration illustrating our design;

FIG. 2 is a top view thereof;

FIG. 3 is a side view thereof;

FIG. 4 is a bottom view thereof;

FIG. 5 is an opposing side view of the side view shown in FIG. 3;

FIG. 6 is a bottom end view thereof;

FIG. 7 is a top end view thereof;

FIG. 8 is a front perspective view of the portable front projection screen shown in an open configuration;

FIG. 9 is a rear perspective view thereof;

FIG. 10 is a front perspective view thereof, in use condition;

FIG. 11 is a side view of FIG. 8;

FIG. 12 is a rear view thereof;

FIG. 13 is an opposing side view of the view shown in FIG. 11;

FIG. 14 is a front view thereof;

FIG. 15 is a bottom view thereof; and,

FIG. 16 is a top view thereof.

The broken lines showing the projector, the display screen and portions of the portable front projection screen and projecting broken lines are included for the purpose of illustrating environmental structure and form no part of the claimed design.
